UNITED STATES PATENT OFFICE.

ALFRED L. ROWE, OF ST. LOUIS, MISSOURI, ASSIGNOR TO THE MISSISSIPPI GLASS COMPANY, OF MISSOURI.

DESIGN FOR SHEET-GLASS.

SPECIFICATION forming part of Design No. 17,736, dated September 20, 1887

Application filed August 1, 1887. Serial No. 245,900. Term of patent 7 years.

To all whom it may concern:

Be it known that I, ALFRED L. ROWE, a citizen of the United States, residing at the city of St. Louis, in the State of Missouri, have invented and produced a new and original Design for Sheet-Glass, of which the following is a specification, reference being had to the accompanying drawing, forming part thereof.

As shown by the drawing, my design is that of a sprig of oak-leaves carrying acorns. The particular arrangement exhibited on the drawing represents one acorn in the center, four acorns with their stems projecting from beneath the central acorn and at right angles to each other, and four oak-leaves projecting from beneath the central acorn, these oak-leaves being at right angles to each other and arranged

in such relation to the projecting acorns that there will be one acorn on either side of each oak-leaf.

The design exhibited in the annexed drawing is placed upon the sheet of glass in any suitable manner.

I claim—

The configuration of the design shown in the annexed drawing when applied to sheet-glass.

In testimony whereof I have affixed my signature, in presence of two witnesses, this 22d day of July, 1887.

ALFRED L. ROWE.

Witnesses:

PAUL BAKEWELL,
S. L. SCHRADER.
